UNITED STATES PATENT OFFICE.

WILLIAM M. MELLING, OF CHICAGO, ILLINOIS, ASSIGNOR OF FORTY-FIVE ONE-HUNDREDTHS TO ANTHONY DOERFLER, OF CHICAGO, ILLINOIS.

TIMING DEVICE.

1,087,803.

Specification of Letters Patent.

Patented Feb. 17, 1914.

Application filed April 24, 1913. Serial No. 763,260.

To all whom it may concern:

Be it known that I, WILLIAM M. MELLING, a citizen of the United States, and a resident of the city of Chicago, county of Cook, 5 and State of Illinois, have invented certain new and useful Improvements in Timing Devices, of which the following is a specification.

My invention relates to timing mechanism 10 for internal combustion engines and more particularly to the class of such engines which are used in motor-cycles and the like.

The object of this improvement is to provide a single cam gear having integrally 15 formed cams adapted to consecutively operate the intake and exhaust valves of an internal combustion engine.

The invention consists in the combinations and arrangements of parts hereinafter 20 described and claimed.

The invention will be best understood by reference to the accompanying drawings forming a part of this specification, and in which—

25 Figure 1 is a side elevation of an internal combustion engine equipped with my improvement and having a portion of the casing removed to expose certain of the working parts, Fig. 2 is a fragmental section of 30 the same taken on a plane immediately behind the timing gears, Fig. 3 is a fragmental section taken on line 3—3 in Fig. 2, and Fig. 4 is a fragmental section taken on line 4—4 in Fig. 1.

35 The preferred form of construction as illustrated in the drawings comprises an internal combustion engine having two cylinders 5 although the device may be modified for use on engines having other numbers 40 of cylinders without departing from my invention. The engine is provided with cylinders 5, each having an intake valve operated by the valve stem 6 in the usual manner and an exhaust valve operated by an 45 exhaust valve stem 7, in the usual manner. Said valve stems 6 and 7 are provided with compression springs 8 in the conventional manner to resiliently maintain them in closed position. Each of the valve stems 5 50 and 6 is operated by means of a plunger rod 9 mounted in a suitable housing 10. The plunger rods 9 and housings 10 are of conventional construction. The lower ends of plunger rods 9 may be rounded as shown

or provided with roller bearings when so desired.

The engine is provided with a conventional crank shaft 11 carrying a spur gear 12 on one end, as indicated in Figs. 1 and 2. In engines of the four-cycle type the timing gear 13 is of such a size as to rotate in the relation of 1 to 2 of the crank shaft. The size of the gears 12 and 13 may be varied and any other cycle-type used. The gear 13 is rotatably mounted on the stud 14 secured to the casing of the engine. Said gear is provided with an internal cam 15 formed in one of its sides and an external cam 16 formed on its other side substantially as indicated. These cams are of such sizes and 70 timed in a manner to operate the intake and exhaust ports of the engine in the conventional manner.

Provided on the casing of the engine in substantially the positions indicated in 75 Figs. 1 and 2 are studs 17 on which are pivotally mounted bell crank levers 18 and 19. Each pair of bell crank levers 18 and 19 are mounted on one of the pins 17 and each having one arm engaging the lower 80 curved end of one of the plunger rods 9 which operate the valve stems 6 and 7. The other arm of each of the bell crank levers 18 and 19 are provided with cam rollers 20. The cam roller 20 on the bell crank 18 is in 85 engagement with the internal cam 15 and the other roller 20 on bell crank 19 is in engagement with the external cam 16.

The pivotal points 17 of the bell crank levers 18 and 19 are placed apart and in such 90 positions as will cause the proper operation of the intake and exhaust valves of both of the cylinders 5 as will be readily understood upon reference to Figs. 1 and 2. The cams 15 and 16 are spaced apart sufficiently to effect proper opening and closing of the intake and exhaust valves of the engine to cause correct operation of said engine. With this construction it will be observed that only one timing gear and two timing cams 100 is necessary and that by disposing the cam levers in the positions indicated the cylinders are properly timed with respect to one another and with respect to themselves.

While I have illustrated and described 105 the preferred form of construction for carrying my invention into effect, this is capable of variation and modification without

departing from the spirit of the invention. I, therefore do not wish to be limited to the precise details of construction set forth, but desire to avail myself of such variations and modifications as come within the scope of the appended claims.

Having described my invention what I claim as new and desire to secure by Letters Patent is:

1. In an internal combustion engine, the combination of intake and exhaust valves; a timing gear; an internal cam on said timing gear; an external cam on said timing gear; bell crank levers, each having one arm engaging one of said cams and its other arm operatively connected with one of said valves, substantially as described.
2. In an internal combustion engine, the combination of intake and exhaust valves; a timing gear; an internal cam in one side of said timing gear; an external cam on the other side of said timing gear; a bell crank lever having one arm operatively connected with said internal cam and its other arm operatively connected with said intake valve; and a bell crank lever having one arm operatively connected with said external cam and its other arm operatively connected with said exhaust valve, substantially as described.
3. In an internal combustion engine, the

combination of a plurality of cylinders; intake and exhaust valves in each cylinder; a timing gear; an internal cam in one side of said timing gear; an external cam on the other side of said timing gear; bell crank levers operatively connecting said internal cam with said intake valves; and bell crank levers operatively connecting said external cam with said exhaust valves, substantially as described.

4. In an internal combustion engine, the combination of a plurality of cylinders; intake and exhaust valves in each cylinder; a timing gear; an internal cam in one side of said timing gear; an external cam on the other side of said timing gear and formed integral therewith; bell crank levers operatively connecting said internal cam with said intake valves and adapted to operate the latter successively; and bell crank levers operatively connecting said external cam with said exhaust valves and adapted to operate the latter successively, substantially as described.

In testimony whereof I have signed my name to this specification in the presence of two subscribing witnesses.

WILLIAM M. MELLING.
